UNITED STATES PATENT OFFICE

124,897

DESIGN FOR A FLAME DETECTOR

Harry C. Grant, Jr., New York, N. Y., and Albert Manhartsberger, Bloomfield, N. J., assignors to Specialties Development Corporation, Bloomfield, N. J., a corporation of New Jersey

Application April 13, 1940, Serial No. 91,670

Term of patent 14 years

To all whom it may concern:

Be it known that we, Harry C. Grant, Jr., a citizen of the United States, residing in New York, in the county of New York and State of New York, and Albert Manhartsberger, a citizen of the United States, residing in Bloomfield, in the county of Essex and State of New Jersey, have invented a new, original, and ornamental Design for a Flame Detector, of which the following is a specification, reference being had to the accompanying drawing, forming a part hereof.

Figure 1 is a corner elevational view of a flame detector showing our new design.

Figure 2 is a rear view of the device of Figure 1, and

Figure 3 is a top plan view of the detector.

We claim:

The ornamental design for a flame detector, substantially as shown.

HARRY C. GRANT, JR.
ALBERT MANHARTSBERGER.
